UNITED STATES PATENT OFFICE

2,548,290

CARTRIDGE FUSE

Lewis Detch, Wilkinsburg, Pa.

Application February 15, 1946, Serial No. 647,737

6 Claims. (Cl. 200—131)

1

This invention relates to improvements in cartridge fuses and particularly of the knife-blade terminal type provided with a renewable fuse.

One of the primary objects of the present invention is to prevent in such fuses sudden, direct venting at the ends of the fuses, of gases generated within the fuse under overload, short circuit or blowouts, and to momentarily retard such venting so as to decrease the extent to which the fusible member will be burned out, and consequently lessen the amount of gas generated by the fuse under such blowouts.

Another object of this invention is to provide a cartridge type fuse having improved means for venting the interior of the fuse casing to relieve the same from high pressures after a short circuit or blowout of the fuse, while at the same time releasing only relatively cool gases.

Yet another object of the invention is to provide means for controlling the liberation of arc gases and to cool the escaping gases by means of tortuous metallic contacts, thereby preventing the emission of flames through the vents.

Still another object of the invention is to provide a cartridge fuse which can be readily and thoroughly cleaned of fused metal incident to blowing of the fuse.

A still further object of the invention is to provide a renewable cartridge fuse with means whereby the threads of the fuse link retaining screws can be fully protected from fused metal incident to blowing of the fuse link, so that the same may be readily unscrewed when replacing a fuse link.

Another object of the invention is to provide such fuses with improved means for rigidly anchoring the ends of the fibre connecting bar to the tongues of the knife blade terminals.

Further objects of the invention are to provide a cartridge fuse of the type specified which is simple in its construction and arrangements without complicating the same so as to prohibitively increase the cost of manufacture.

To the accomplishment of these and such other objects as may hereafter appear the invention consists of the novel construction, combination and arrangement of parts herein specifically described and illustrated in the accompanying drawings, wherein is shown an embodiment of the invention, but it is to be understood that changes, variations and modifications may be resorted to which come within the scope of the claims hereunto appended.

In the drawings wherein like numerals of reference designate corresponding parts throughout the several views,

Figure 1 is a side elevational outline view of

the complete device, partly exposing the interior thereof.

Figure 2 is a view in side elevation showing the knife blade terminal assembly partly inserted in the casing, with the end elements partly disassembled.

Figure 3 is an enlarged, fragmentary side elevation, partly in cross-section, showing an assembled end of the device.

Figure 4 is an enlarged, fragmentary top view of an end of the knife blade terminal assembly.

Figure 5 is an enlarged top plan view of one of the discs as used in this invention.

Figure 6 is a sectional view on line 6—6 in Figure 5.

Figure 7 is an enlarged top plan view of the lipped discs as used in this invention.

Figure 8 is a sectional view on line 8—8 in Figure 7.

Figure 9 is an isometric view of the channelled member as used for retaining the fibre bar in rigid position.

Figure 10 is an enlarged, fragmentary side view of the knife blade terminal showing the plain disc and the lipped disc assembled on the tongue end of the terminal.

Figure 11 is a side view of the knife blade terminal assembly.

Figure 12 is a top view of Figure 11.

Figure 13 is an isometric view of one of the end closures drawn to an enlarged scale.

Figure 14 is a view on line 14—14 in Figure 12.

Figure 15 is a sectional view on line 15—15 in Figure 12.

Figure 16 is a modification of Figure 4 showing a channelled retaining member for the fibre bar.

Figure 17 represents a sectional view on line 17—17 in Figure 16.

Figure 18 is an isometric view of the channelled fibre bar retaining member.

Figure 19 is a fragmentary, longitudinal, cross-sectional view of a modification of a cartridge fuse, the knife blade terminal assembly being in outline.

Figure 20 is a top view of Figure 19, partly in outline.

Figure 21 is an enlarged, isometric view of one of the knife blade terminals showing the inner disc and the outer disc secured to the blade.

Figure 22 is an enlarged, isometric view of the end closure as used in this modification.

Figure 23 is a detail plan view of the inner disc as used in this modification.

Figure 24 is a side view of Figure 23.

Figure 25 is a detail plan view of the outer disc as used in this modification.

Figure 26 is a side view of Figure 25.

In referring to the embodiment of the cartridge fuse 20, 21 represents the usual tubular casing of fibre insulation, having a pair of externally threaded metallic end-sleeves 22 secured to said casing by rivets 23, or otherwise.

A pair of brass caps 24, adapted to be screwed onto said end-sleeves 22, are provided at the outer ends thereof with internal flanges 25, and to provide a finger hold for attaching or removing said caps the outer parts thereof are knurled as indicated by the numeral 26.

The knife blade terminal as shown in Figures 11 and 12 comprises a pair of copper knife blade terminals 27 extending out of the caps 24 and having reduced tongues 28 extending into the sleeves 22 of the fibre casing 21.

The terminals 27 are connected together by a fibre bar 29 which is attached to the opposing tongues 28 of the terminals. In order to retain said fibre bar 29 rigidly in assembled position I provide a channeled retaining member 30 as shown in Figures 4, 9, 11, 12 and 15 inclusive. This retaining member will be explained later.

As shown in Figure 10, the reduced inner end or tongues 28 of terminals 27 form right angled rear end corners 32 on the wide portions of the terminals. The knife blade terminals 27 are provided with plain spacing discs 33 and lipped spacing discs 34 both of which have a rectangular aperture 35 to snugly accommodate the rectangular tongue ends 28 as shown in Figures 4 and 10.

The plain spacing discs are shown detailed in Figures 5 and 6 and the lipped spacing discs are shown detailed in Figures 7 and 8.

It will be noted that the lips 31 of the lipped spacing disc 34 are rounded to conform to the shape of the edges of the terminals 27 in order to fill the space between the corners 32 of the terminals and the plain disc 33 when in final position as shown in the various figures. In order to permanently retain these discs in position the tongues 28 are upset against discs 33, as indicated by the numeral 36 in Figure 4.

In assembled position, the plain discs 33 fit with a slight clearance around the interior of the end sleeves 22 at the outer ends thereof, while the lipped discs 34 form concentric bosses 37 the purpose of which will be explained later.

The plain discs 33 are provided with a pair of diametrically opposite, peripheral notches 38 serving a purpose also explained later.

End closures 39, as best shown in Figure 13, are provided which fit within the cap 24 and are confined between the flanges 25 of caps 24 and the outer faces of the plain spacing discs 33 of the knife blade assembly. These end closures 39 comprise a pair of annular discs in which 40 represents the outer disc and 41 the inner disc. Said outer disc 40 is diametrically slotted, as at 42, to snugly fit over the knife blade terminals 27.

Both, the inner disc 41 and the outer disc 40 have the same outside diameter. Disc 41 has a concentric hole 43 slightly larger in diameter than the outside diameter of the lipped spacing discs 34, so as to provide a clearance between the outside diameter of disc 34 and the inside diameter of hole 43 when in assembled position (Figure 4).

When assembled, the outer disc 40 and the inner disc 41 form the end closure 39 and this is accomplished by riveting both discs together by means of a pair of pin-rivets 44 placed at right angles to the slot 42. The inner disc 41 is also provided with diametrically opposite notches

45 which correspond, when assembled, to the ends of the diametrical slot 42 in disc 40.

In Figure 4 it will be noted, that the pin-rivets 44 extend beyond the inner face 46 of the inner disc 41 and extend also outwardly so that part of said pin-rivets 44 extend into the slots 47 located at the edges 48 of the sleeves 22.

The caps 24, when in final position, completely cover the slots 47 of the end sleeves 22 of fibre casing 21, and the end closures 39 substantially close the caps 24 on the inner face of the flange 25 thereof.

As heretofore mentioned, channeled members 30 are provided in order to retain the fibre bar 29 in rigid position, such as shown detailed in Figure 9 or assembled in Figures 4, 11, 12 and 15. These channeled members 30 are made of sheet metal and comprise a rectangular base or web 49 having a central aperture 50 and three right angled sides or flanges 51, 52 and 53.

The side 52 of the channeled member 30 may be permanently secured to the inner face 54 of the spacing disc 33 by soldering, or otherwise.

As best shown in Figures 11, 12 and 15 the right angled side 52 abuts the inner face 54 of spacing disc 33 and is held thereon permanently as above explained.

Obviously, the fibre bar 29 serves mainly as a retaining connection between the two similar ends of the knife blade terminals 27, should the fusible link-member 55 melt after a blow-out. The ends 56 of said fibre bar 29 snugly fit between the angle sides 51 and 53 and for best result the ends 56 should be in abutment with the inner face 57 of said angle side 52.

As will be noted, the aforesaid fusible link-member 55 contacts one face of the tongues 28 of knife blade terminals 27, while the fibre bar 29 contacts the opposite face of the tongues 28, so that the channeled retaining member 30 embraces the ends of the fibre bar 29 in a manner as shown in Figures 4, 11, 12 and 15.

The fusible link member 55, the fibre bar 29 and the channeled retaining members 30 are securely held to the tongues 28 of the terminals 27 by means of so called "drive-in machine screws" 58 such as shown in Figure 4. These screws are available in the open market and could be used advantageously thereby eliminating undesirable play around the parts and the screw, also resulting in improved electrical connections because the screw-thread 59 of said screw 58 worms itself into the parts and holds very effectively under vibration, impact or shock and wide ranges of temperature conditions to which fuses are subject.

It is to be noted that the fibre connecting bar 29 spaces the knife blade terminals 27 between the shoulders x as indicated in Figure 12, a distance apart slightly greater than the overall length of the casing 21, including the end sleeves 22 as part of the casing 21, see Y in Figure 3, so that when the caps 24 are screwed home on said end sleeves 22 and with the flanges 25 abutting the closures 39, annular gas vents 60, one of which is shown in Figure 3, are provided between the outer ends of said casing 21 and the discs 33 and 34 communicating with the open edges of the slots 47 which are substantially closed, otherwise than at said edges, by the said caps 24 and the end sleeves 22.

As will now be seen, the described fuse is designed to protect instruments connected in, and substances adjacent the circuits and to effect proper protection, the fusible link member 55

5

must open the circuits under exact predetermined conditions of overload and short circuit without endangering surrounding objects or injury to the elements of the fuses.

There are three important standard requirements essential in renewable cartridge fuses, first, there must be definite relations between the internal pressure, second, the rate of gas escape and third, the degree to which the gas is cooled before it reaches the outer atmosphere or surrounding objects.

Under overload, short circuit or blow-outs in the described fuse, the gas may issue from the casing 21 around the edges of the spacing discs 33 and pass into the annular gas vents 60 to the slots 47 in edges 48 of the end sleeves 22 and then out to the atmosphere between the threads of the sleeves 22 and caps 24. Also such gas may seep between the outer discs 40 and inner discs 41 of the end closures 39 to pass into said vents 60 and out of the slots 47 in the same manner. Some of the gas may also seep by the closures 39 and out of the slots 42 therein.

Thus the gas generated within the fuse is forced to escape by tortuous paths whereby the escape of the gas is retarded sufficiently to prevent large portions of the fusible link member 55 from burning through and thereby generating proportionally large quantities of gas in the fuse.

By designing the gas paths so that the gas generated is conducted through tortuous passages, the gas so deflected into different directions is greatly cooled, due to the mass of metallic contact during the escape. This results in safer operations, under blow-outs, and obviates clogging of the casing and other parts so that the same may be easily cleaned when the fusible link member 55 is replaced.

It is to be noted that the described connections of the fusible link member 55 and the fibre bar 29 to the tongues 28 of the knife blade terminals 27 provide for renewing said link member without loosening the fibre bar 29, as will be clear.

Obviously, the knife blade terminals 27, the end closures 39 and the discs 33 and 34 are interchangeable at opposite ends of the fuse, which is a distinct advantage in assembling and replacing parts.

In order to protect any exposed threads of the screws 58 from melted fuse metal after a blow-out I use a cap-nut 61.

After a short circuit or blow-out the complete fusible link member assembly may be withdrawn from the casing 21 by unscrewing one of the caps 24. The link member assembly is then thoroughly cleaned and the mutilated link member is replaced by a new one after which the link assembly is placed into the casing 21 and the cap 24 screwed home.

Figures 16, 17 and 18 show a slight modification of the channeled fibre bar retaining member 30 shown in Figure 9.

In this modification the fibre bar retaining member 62 comprises a base 63 having a pair of opposite upstanding sides 64 to form a channel. A central aperture is provided to accommodate the drive-in machine screw 58.

In this construction, the upstanding sides 64 embrace the fibre bar 29 and the tongues 31 of the terminals 27, thereby preventing any movement of bar 29, as will be noted.

It remains now to describe Figures 19 to 26 inclusive, in which is shown a slight modification of the cartridge fuse previously described.

The above-mentioned modification relates to

6

cartridge fuses in which the tubular fibre casing is considerably larger in diameter than the one described previously, while the size of the knife blade terminal assembly remains the same.

The general structure of the knife blade assembly is substantially the same in design and size as the one best shown in Figures 11 and 12, with the exception that the fusible link member 65 and the fibre bar 66, both shown in Figures 19 and 20, are somewhat longer, and due to the fact that the tubular fibre casing 67 in this modification has been enlarged, the inner spacing disc 68 (Figures 23-24) and the outer spacing disc 69 (Figures 25-26) replace the discs 33 and 34 respectively, shown in Figures 5-6 and 7-8.

End closure 70, shown best in Figure 22, replaces the end closure 39 shown in Figure 13 to take care of the larger fibre tube or casing 67 and the inner and outer discs 68 and 69 respectively.

Said inner spacing disc 68 shown detailed in Figures 23 and 24 comprises a flat member having arcuate edges 71 and parallel straight edges 72. A central slot 73, in parallel alignment with said edges 72, is provided that fits over the tongue portion 28 of the knife blade terminal 27.

Said outer spacing disc 69, detailed in Figures 25 and 26 comprises a flat member having a circular middle portion 74 narrowed down ends 76, as shown, and having a central slot 75 in parallel alignment with the edges of the narrowed down portion. Both the inner and outer discs 68 and 69 respectively, are slipped over the tongue portion 28 of the knife blade terminal 27, after which the discs are peened, as indicated by the numeral 77, against the shoulder 78 between the tongue 28 and blade terminal 27 (Fig. 19).

Figure 22 represents a perspective view of the end closure 70, as used in this modification, and the same is composed of an annular inner disc 79 and an annular outer disc 80. Said inner disc 79 is provided with a central cut-out portion 81 having a configuration similar to the outline of the outer spacing disc 69, shown detailed in Figure 25, so that the cut-out portion 81 of inner disc 79, when in final position, will clear the contour of said disc 69 in a manner as shown in Figures 19 and 20.

The annular outer disc 80 is provided with a centrally disposed, elongated slot 82 which fits over the knife blade terminal 27.

A pair of outwardly extending pins 83 are provided which also serve to secure both discs 79 and 80 together. These pins 83 are spaced apart sufficiently to clear, when assembled, the parallel edges 72 of the inner disc 68 and at the same time penetrate the slots 84 of the end sleeve 35 of the tubular fibre casing 67 to prevent the complete knife blade terminal assembly from turning in the casing.

At this time it should be noted, that the heretofore described cartridge fuse is primarily intended to be used for a voltage not to exceed 250, while the herewith described modification is intended to be used for a voltage from 250 to 600 inclusive.

As is well known in the trade, the vapor generated within the casing 67 by blowing of the fuse member is greater at a high voltage than at a low voltage, and at the same time the internal pressure within said casing increases also in proportion at a higher voltage.

Discs 33 and 34 (Fig. 12 for up to 250 volts) and discs 68 and 69 (Fig. 21 from 250 to 600 volts) when assembled with end closures 39 and 70 respectively are designed to provide a baffle to

prevent excessive escape of the gases within the cartridge after a blow-out. The lips 31 of disc 34 and the ends 76 of disc 69 respectively serve mainly to provide a long tortuous path for the escaping gases thereby considerably reducing the internal pressure within the cartridge and also reducing the violence of the pressure after a blow-out. In addition, due to the various metallic contacts the gases are considerably cooled when escaping through the gaps between the slot of the cap and the knife blade terminals. Another important feature of the lips of disc 34 has been previously explained.

In order to reduce the vapor generated in a 600 volt cartridge fuse and the internal pressure within the casing in proportion to a 250 volt cartridge fuse, the knife blade terminal of the 250 volt cartridge fuse is made longer and the fibre casing is made larger in diameter.

Since the casing 67 in this modification is longer than the one previously described, the fibre bar 66 and the fusible link member 55 are also longer and in consequence, the discs 68 and 69 shown in Figures 23 to 26 inclusive replace the discs 33 and 34 of the first described cartridge fuse.

The end closure 70 for the 600 volt cartridge fuse shown best in Figure 22 slightly differs from the 250 volt end closure shown in Figure 13, as will be observed.

At this time it should be mentioned that the main reason for enlarging the tubular casing and also lengthen same when using for 600 volts is to provide more space within the casing for the additional vapor generated when blowing a fuse under higher voltage, also retaining sufficient pressure within the casing to aid in quenching the arc formed after a fuse blow, but, at the same time, enough vapor must be released to prevent bursting of the fibre casing.

In order to sufficiently cool the vapor before being permitted to escape, the vapor is forced through tortuous paths, as indicated by the arrows in Figures 19 and 20.

The foregoing, it is believed, will suffice to impart a clear understanding of the invention, both as regards structure, cooperation, and the advantage thereof.

Manifestly, the invention as described, is susceptible of modifications without departing from the invention and right is herein reserved to said modifications as fall within the scope of the appended claims.

What I claim is:

1. A cartridge fuse of the class described, a tubular casing having threaded end sleeves; a removable fuse link supporting structure within said casing; knife blade terminals; an insulating bar for connecting said knife blade terminals; a fuse link member; said terminals having a tongue reduced in width to form a shoulder; a lipped disc and a plain disc, both having a diametrical slot to receive said tongue; said lipped disc in abutment with said shoulder, said plain disc in abutment with said lipped disc, both discs permanently secured to said tongue; said insulating bar attached to one face of said tongue and the fuse link member attached to the other face of said tongue; a channeled bar retaining member having a base and upstanding sides adapted for holding said insulating bar against longitudinal and rotary displacement, one of said upstanding sides in abutment with and secured to the face of said plain disc; an end closure provided with a diametrical slot conforming to a section of said ter-

75
8
minal and adapted to receive the lips on the lipped disc and threaded caps screwed onto the threaded end sleeves of said tubular casing.

2. A cartridge fuse comprising a tubular casing of insulating material having a metallic sleeve at each end and a fuse-link supporting structure removably disposed in said casing comprising knife-blade terminals projecting into the outer ends of said sleeves, an insulating bar secured to the inner ends of said terminals and extending through said casing maintaining the terminals in spaced relation, a pair of diametrically slotted discs fitted on each terminal in closely abutting relation, the outer of said discs having circumferentially spaced portions projecting radially outward from the edge thereof, said outer discs having a diameter less than the width of the terminals, diametrically slotted end closures fitted on said terminals outwardly of said discs, each closure having a recess in its inner face shaped to accommodate said outer disc whereby to provide a tortuous escape passage for gases from the interior of said casing, and an annular cap screwed onto each sleeve effective to hold the closure against the outer disc.

3. A fuse as defined by claim 2 characterized by the inner ends of said terminals being reduced in width forming a shoulder thereon and said outer discs abutting said shoulders.

4. A fuse as defined by claim 2 characterized by the sleeves having notches in their outer edges spaced circumferentially thereof and the inner discs having notches in their edges positioned to register with the notches in said sleeves, said closures having inwardly projecting dowel pins positioned to fit into the notches in said inner discs and the notches in said sleeves.

5. A fuse as defined by claim 2 characterized by a channel-shaped retaining member secured to each of the inner discs and embracing the ends of said bar.

6. In a renewable fuse of the class described, a tubular casing having an annular cap threaded onto each end, a fusible link member and a connecting bar within said casing, a knife blade terminal protruding through said caps and having a tongue end adapted to be connected to corresponding ends of said link member and connecting bar, a pair of spacing discs fitted side by side on each of said terminals and means to connect the inner ends of said terminals to corresponding ends of the link member and connecting bar comprising a channeled member provided with a flange secured to the inner disc opposed to the end of the channel member and flanges straddling the end of said connecting bar and a screw extending through each of said channeled members, the tongue end of the adjacent terminal and one end of the link member and connecting bar.

LEWIS DETCH.
